(57) **CLAIM**

The ornamental design for a skid steer loader with lift arms, as shown and described.

DESCRIPTION

FIG. 1 is a rear perspective view of a skid steer loader with extendable lift arms embodying our new design;

FIG. 2 is a right side view thereof;

FIG. 3 is a left side view thereof;

FIG. 4 is a top plan view thereof;

FIG. 5 is a rear view thereof;

FIG. 6 is a front view thereof; and,

FIG. 7 is a bottom plan view thereof.

The broken line showing is for illustrative purposes only and forms no part of the claimed design.
